SPEED CHANGE FOR RECORDING APPARATUS

Paul Stead Gay, Charlotte, Mich., assignor to Wilcox-Gay Corporation, Charlotte, Mich., a corporation of Michigan

Application October 8, 1940, Serial No. 360,288

9 Claims. (Cl. 74—190)

This invention relates to record apparatus which involves the use of a turntable upon which a recording disk is placed and more particularly to a means for changing the speed of rotation of the turntable and is an improvement on my application Serial No. 320,823, filed February 26, 1940.

The primary purpose of my invention is to provide an adjustment for varying the speed of rotation of the turntable in accordance with different records where the records have been cut at different speeds or where the records have been manufactured so as to be operated at different speeds. Thus in certain types of sound recording work, a turntable is operated at a speed of only 33½ revolutions per minute instead of the normal 78. A speed adjustment of the type herein described may be utilized for the purpose of adjusting the speed of rotation of the turntable to accommodate records which should be played at different speeds.

Such "fast" and "slow" adjustments may, of course, be used for other purposes although primarily it has been designed by me for use in connection with the purposes above mentioned.

Thus, for instance, in apparatus now on the market of the type described in my application above mentioned, the same turntable and operating mechanism therefor is used both for cutting the record and for playing the record back.

When a record is cut on the turntable the power demand is comparatively much greater than when a record is being played back, since the cutting stylus must actually remove material from the surface of the disk in order to create the groove, while in playing back the recording needle need merely follow the groove which has already been cut.

Such differences in power demand cause differences in the actual load upon the turntable and hence upon the operating means therefor, tending to cause a difference in speed. Such difference in speed may, under certain circumstances, be sufficient to actually change the quality of the voice during the playing back of the record; that is, the record, when played back when only the transcription needle need follow the groove, is under a lighter load and hence the tendency is for it to rotate faster, thus raising the pitch of the voice somewhat. When the turntable is slowed down to a predetermined degree, the quality or timbre of the recorded voice is once more recognizable.

My present invention may be used for changing the speed of rotation of the turntable so as

to correct for these factors; that is, the turntable is set so that it will normally be rotated at a slightly greater speed when a record is being cut than when it is being played back.

5 The differences in the speed adjustment need not be great but should in the ordinary case be only sufficient to compensate for the difference in load.

Thus in accordance with my invention when a 10 record is being cut on the turntable, the speed adjustment should be set at "fast" or "cut." The added load on the turntable owing to the cutting operation would then tend to slow down the operation of the turntable. If the record were then played back with the ordinary recording needle while the speed adjustment is at the same setting, then, owing to the decreased load, the turntable would be permitted to rotate faster and thence change the pitch of the recording. Accordingly, to compensate for this 15 operator may move the speed adjustment over to "slow" or "play," thus slowing down the turntable for playing the record.

The speed adjustment should be such in this 20 case that the turntable, when the record is being played, would then be rotating at the same speed as it was rotating when an actual cutting was being made and thus by this type of adjustment the quality of the record is not changed during 25 the playing back by reason of any variations in the speed of rotation of the turntable.

The particular type of speed adjustment of 30 my device lends itself readily to an adjustment for stopping the turntable while the operating apparatus therefor remains in motion. This materially reduces the masses of the members which must be brought to a stop.

Ordinarily, in order to stop the rotation of the 35 turntable the motor and other members operating the same must be stopped. The speed adjustment of my invention may be arranged to have a "stop" adjustment so that the turntable is disengaged from the operating mechanism therefor and only the mass of the turntable need be brought to a stop.

40 Preferably, my invention is utilized in connection with and incorporated in the principle of power transmission described in my application above mentioned; that is, the motor spindle is not directly connected to the turntable but instead frictionally bears against an idler which is caused to rotate thereby, the said idler contacting a downturned edge or flange of the turntable, thus transmitting the motion from the 45 spindle of the motor to the turntable.

The operation of my invention depends upon the changing of this idler connection between the spindle of the motor and the flange of the turntable and the utilization of at least a number of different idlers which may be successively placed in operative position between the spindle of the motor and the turntable.

In order to bring the turntable to a stop, I may also arrange these idlers in such a position that at one setting thereof neither of the idlers is 10 operatively engaged between the spindle of the motor and the turntable.

An important object of my invention, therefore, is to so arrange the driving connection between the operative means and the turntable of the recording apparatus that the speed of rotation of the turntable and recording apparatus may be varied.

Still another object of my invention is to so arrange the power connection between the driving means and the turntable that the said driving connection may selectively be removed from between the spindle of the motor and the turntable, thus permitting the turntable to be brought to a stop without stopping the motor or other operating parts for the turntable.

Another more specific object of my invention is to arrange a pair of idlers on a single floating carrier in such a manner that different idlers may selectively be brought into operative engagement between different portions of the motor spindle and the turntable to effect different speeds of operation or rotation of the turntable.

These and other objects of my invention will in part be apparent and in part pointed out in the following description and drawings in which:

Figure 1 is a view in perspective partially broken away of the turntable operating apparatus embodying the subject matter of my invention.

Figure 2 is a top view of a portion of the construction of Figure 1 showing the members in the position of Figure 1.

Figure 3 is a view corresponding to Figure 2 showing a different position of the members thereof.

Figure 4 is a view corresponding to Figures 2 and 3, showing the "stop" position of the members thereof.

Figure 5 is a cross-sectional view taken along line 5—5 of Figure 3.

Figure 6 is a cross-sectional view taken on line 6—6 of Figure 5.

Figure 7 is a view corresponding to that of Figure 2 showing a slightly modified method of operating the idler change mechanism.

Figure 8 is another view corresponding to the view of Figure 2 showing a still further modified form of the idler change mechanism.

Figure 9 is a cross-sectional view taken on line 9—9 of Figure 7.

Figure 10 is a cross-sectional view taken on line 10—10 of Figure 8.

Referring now to Figure 1, I have here shown in somewhat schematic arrangement the operating mechanism for use in connection with the turntable which is utilized for both cutting records and playing the records back. This turntable operating mechanism is constructed in substantially the same manner as that of the recording apparatus described in my prior application above mentioned, and comprises a base plate 20 carrying a hollow post 21 in which is rotatably journaled a post 22 which carries a platform 23 upon which is mounted a playback arm 24.

The playback arm 24 is rotatable in a vertical

plane about the platform 23 and the platform 23 is rotatable in a horizontal plane with respect to the base plate 20 so that the playback arm which normally carries a playback needle may be readily placed in operative connection with a recording disk mounted on the turntable and so that it may readily follow a groove in the recording disk.

The base plate 20 also carries a hollow post 26 in which is rotatably and slidably journaled the post 27 to which is secured the platform 28. The cutting arm 29 is pivotally mounted by means of the members 30 upon the platform 28 so that the cutting arm may be rotated in a vertical plane. The platform 28 may, as has above been mentioned, be rotated in a horizontal plane and thus the cutting arm may be placed in operative connection with a recording disk upon the turntable.

The cutting arm is driven by means of the arm 31 and the follower 32 which may be releasably engaged with the screw 33 which may be driven from the motor or, in the preferred form, from the turntable. The operation of the cutting arm and a full description of all of the members thereof is set forth in my application Serial No. 320,823, filed February 26, 1940 and forms no part of the present invention.

It is sufficient to note that the cutting stylus 30 of the cutting arm when the stylus is placed upon a disk on the rotating turntable offers sufficient resistance to the rotation of the turntable to tend to slow the turntable down, thus making it desirable to use the speed adjustments of the type hereinafter to be described.

The turntable 40 is rotatably mounted on the spindle 41. The said turntable has a downturned flange 42 against which the operative connection between the motor and the turntable may bear.

The motor (not shown) is secured beneath the mounting plate 43 which in turn is mounted on the base plate 20. The motor spindle 44 projects through an opening in the mounting plate 43 above the surface of the base plate 20. The specific mounting of the motor and the arrangement thereof to reduce power pulses and consequent shocks therefrom is described in my application above mentioned and a description thereof is not necessary for an understanding of the present invention.

In my application aforementioned I describe the manner in which motive power is transmitted from the spindle 44 through the idler mounted upon its floating mounting to the flange of the turntable. In the present application two such idlers 50 and 51 are shown. Each of these idlers has a tire, 52 and 53 respectively, of resilient compressible material preferably rubber and adapted to transmit power by friction.

Each of the idlers is mounted, as is more specifically hereinafter described, upon the floating idler carrier 55. The floating idler carrier 55 is held upon the mounting plate 43 by means of the washer 56 indicated by dotted lines in Figure 2 and more clearly shown in cross-section in Figure 5. The washer 56 is fixedly positioned upon the pin 57 by means of the lock nuts 58, the pin 57 being supported by the mounting plate 43.

The opening 59 in the floating idler mounting 55 is larger than the diameter of the pin 57 so that the floating mounting 55 can accommodate itself to the position of the idler and so that the floating mounting spring may also exert pressure upon the idler for the purposes described in

my application above mentioned and for the more specific purposes hereinafter described.

A spring 60, captured at one end at 61 in the mounting plate 43, is guided by the lug 62 struck up from the mounting plate and engages the floating idler mounting 55 at the lug 63 thereof by which it is attached to the floating idler mounting. The tendency of the spring is to cause the floating mounting bar to move to such a position that the idlers are pressed toward the spindle 44 and the rim of table 42. The lug 70 struck up from the mounting plate 43 engages an opening 71 in the floating idler mounting in order to provide a point about which the floating idler mounting may rotate. The opening 71 in the floating idler mounting is slotted to permit the floating idler mounting to move slightly during the adjustment of the idlers.

Likewise the fact that the opening 59 is much larger than the opening 57 permits the floating 20 idler mounting to adjust itself to the appropriate position for engagement of the idlers. As is seen more particularly in the cross-sectional view of Figure 5, idler 51 is rotatably mounted on the bearing 80. The said bearing 80 is itself rotatably mounted on the pin 81 which is secured to the floating idler mounting 55. The pin 81 has a washer 82 secured thereto and bearing against the upper face of the idler mounting 55 and the head of the pin 83 is secured against the other 25 face of the idler mount 55, thus supporting and positioning the pin 81.

The bearing sleeve 80 carries fixedly secured thereto and therefore rotatable therewith at the upper end thereof an arm 90, the arm having a perforation which is mounted over the sleeve 80 and carrying a set screw 91 which is rotatable into engagement with the surface of the sleeve 80 in order to secure the arm thereto. The opposite end of the arm 90 has secured thereto a pin 92 the lower end of which is mounted in a suitable opening in said arm. The projecting end of the pin 92 has at 93 a bearing surface upon which the idler 50 carrying the tire 52 is rotatably mounted.

The lower end of the sleeve 80 is connected to or integrally extended into a shift lever 100. Movement of the shift lever to the various positions shown, for instance, by the drawings of Figures 2, 3 and 4 will cause the sleeve 80 to rotate. Rotation of the sleeve 80 will result in a corresponding rotation of the arm 90 and a corresponding rotation therefore of the pin 92 and its extension 93 and will thus cause the center of the idler 50 to swing about the center of the idler 51 so as to vary the positions of the idlers with respect to each other.

The speed adjustment herein provided for is one which depends upon the operation of the lever 100 and the movement thereof to three different positions for the purpose of effecting the speed changing operation herein described. Preferably, however, in the embodiment herein shown the two idlers are of the same diameter and a variation in the diameter of the motor spindle 44 is relied upon to obtain the change in speed.

Thus, as is seen in Figures 1 and 6, the spindle 44 has a slow speed portion or a restricted diameter portion 101 at its upper end and a higher speed portion or an enlarged diameter portion 70 at its lower end 102.

The high speed portion 102 of the spindle 44 is engageable only with the high speed idler 51 and the low speed or restricted diameter portion 75

101 of the spindle 44 is engageable only with the low speed idler 50.

The idlers 50—51 are low speed and high speed respectively only because they are so positioned 5 that they can engage only a particular portion of the spindle and, in this particular embodiment of the invention, it is only the difference in the diameter of the portion of the spindle which bears against the idler which determines the particular speed variation required.

The purpose of the lever 100 is therefore to either swing the high speed idler 51 against the portion 102 of the spindle or to swing the low speed idler 50 against the portion 101 of the spindle, thereby pushing the high speed idler 51 away from the spindle, or to so position the idlers that neither of them is pressing against both the spindle and the turntable at one time.

As is seen in Figure 1, the members are so arranged that the low speed idler 50 is pressed against the upper portion 101 of the spindle and at the same time is pressed against the flange 42 of the turntable and thus rotative motion from the motor is communicated through the small 25 diameter portion 101 of the spindle to the peripheral portion of the idler 50 and therefrom to the downturned flange 42 which results in rotation of the turntable 40.

By reason of the engagement of the idler 50 against the restricted portion of the spindle 101, the floating mounting 55 has been rotated sufficiently to move the idler 51 out of engagement with the portion 102 of the spindle; and thus even though the idler 51 may be pressed against the flange 42, since it is not pressed against the spindle, no rotative power is communicated from the portion 102 of the spindle to the flange 42 of the turntable, and the only rotative power transmitted to the turntable is that through the 35 restricted portion 101 of the spindle and the idler 50.

When the lever 100 is moved from the position shown in Figure 2 to the position shown in Figure 3, it results in a corresponding rotation of 45 the sleeve 80 and consequently of the arm 90 and of the center or mounting 93 of the idler 50 about the center of the idler 51.

By this operation the idler 50 is brought to bear against the restricted portion 101 of the 50 spindle 44 at such a position that the idler 50 is no longer in engagement with the flange 42 of the turntable. The spring 60 has, however, forced the floating mounting plate 55 over to a position wherein the high speed idler 51 is engaged against the enlarged diameter portion 102 of the spindle and is simultaneously engaged against the flange 42 of the turntable and hence rotative motion is transmitted from the enlarged 55 portion of the spindle to the turntable.

When the lever 100 is moved to the position shown in Figure 4, then again the sleeve 80 and its arm 90 is rotated, thus once more swinging the center 93 of the idler 50 about the center of the idler 51 and although the idler 50 is 60 now pressed against the spindle 44, the center 93 of the idler 50 is sufficiently displaced with respect to the center of the idler 51 as to force the idler 51 away from the spindle. Thus in this case the idler 51 is pressed against the flange 42 of the turntable while the idler 50 is pressed against the spindle but neither of the idlers is in engagement with both the spindle and the turntable and hence no rotative power can be transmitted from the spindle to the turntable.

The various different positions above described

will be obvious from an examination of the figures and of the description in connection therewith. It is sufficient to say that in Figure 2 the idler 50 is in engagement between the spindle and the turntable and prevents the idler 51 from being in engagement therewith since the center of the idler 50 is closer to the spindle and hence the action of the spring 60 which tends to rotate the mounting plate 55 is inhibited when the idler 50 engages the spindle and thus the idler 51 cannot be forced against the spindle.

In Figure 3 the center of the idler 50 has been rotated to such a position that the distance between the center of the idler 51 and its portion 102 of the spindle is less than the distance between the center of the idler 50 and its portion of the spindle and hence the idler 51 is permitted to come into engagement with the spindle by the action of the spring 60 and into simultaneous engagement with the flange 42 for the transmission of rotative power.

In the position of Figure 4, the centers of the two idlers are so lined up that the center of the idler 51 is closer to the flange 42 of the turntable and the center of the idler 50 is closer to the spindle, thus preventing complete contact by each of the members with both the spindle and the turntable and hence preventing the transmission of rotative motion.

Thus for the slow speed position the center of idler 50 is moved to such a position that it is closer to both the turntable flange and the spindle than is the center of idler 51. In the high speed position the center of idler 51 is moved to closer position to both the spindle and the flange of the turntable than is the center of idler 50 and for stop position the center of idler 50 is closer to the spindle, and the center of the idler 51 is closer to the flange, thus preventing complete contact by both idlers.

Thus by the movement of the lever and the consequent rotation of the sleeve 80 about the pin 81, it is possible to change from low speed to high speed and vice versa, and to stop the turntable by the means herein described for the purposes hereinabove mentioned. A stopping of the turntable occurs only by reason of the disengagement of the idlers from between the motor spindle and the turntable and hence it is not necessary to halt the motor or other operating members in order to stop the rotation of the turntable.

Likewise it is possible to change from low speed to high speed and back once more without halting the operation of the motor and other operative connections.

The link action when the offset arm 90 is revolved around the post 81, working on a toggle principle, produces a sufficient action to lock the members in the desired position for "fast" or "slow" operation.

Other means may be provided in connection with the lever 100 for releasably locking the lever 100 in the position in which it is left. Such means will now be obvious to those skilled in the art.

The mounting plate 20 may carry any suitable legends which are necessary to indicate what a particular position of the lever 100 may mean. Thus, for instance, the legends "Slow," "Stop," and "Fast" may be placed upon the mounting plate as shown in the figures or the legend "Cut" may be substituted for the legend "Fast" and the legend "Play" may be substituted for the

legend "Slow" or any other suitable legends may be utilized.

Utilizing the same principles, that is, the principle of the rotation of the center of the low speed idler 50 about the center of the high speed idler 51 in order to obtain the various changes in speed, modifications may be made in the manner of obtaining this result.

Thus in cases where the base 20 is depressed so that the turntable rides almost flush with the surface of the plate and the flange of the turntable enters into the depression, the lever may be modified in order to obtain proper operation thereof.

Thus as shown in Figures 7 and 9, the base plate 20 has been depressed at 120 so that the surface of the turntable 40 rides almost flush with the base plate 20 and so that the flange 42 of the turntable rides virtually within the depression.

The mounting plate 55 is constructed and mounted in the same manner and carries the same members as has heretofore been described in connection with Figures 1 to 6 inclusive.

The lever 100', however, is led out through an opening 121 in the wall 122 of the depression 120. This opening is of sufficient width to permit the lever 100' to be moved to each of the three positions as indicated by the dotted lines of Figure 7. The positions of the lever 100' for "Fast," "Slow," and "Stop" in Figure 7 are the same as the positions of the lever 100 for the same operations in Figures 1 to 6 inclusive.

The end of the lever 100' is engaged in an opening 124 in a link 125. The link 125 extends around the outside of the wall 122 of the depression and, if desired, may be guided by the additional track member 126 which is secured beneath the depression 120.

40 The link 125 has at the opposite end thereof from the end at which it engages the lever 100' an indicating portion 127 which extends up through a slot 128 in the base plate 20 of the recording apparatus.

45 The indicating portion 127 which extends through the slot 128 may be, if desired, bent over at 129 and shaped or formed in any suitable manner to provide a means for grasping the said indicating portion and moving the same as well as a means for indicating the setting of the lever 100'.

50 When the portion 129 is set as shown in Figure 7, then the lever 100' is likewise set as is shown in Figure 7 and in accordance with the foregoing explanations with respect to Figures 1 to 6, it will now be obvious that the mechanism is set for operation at the slow speed.

55 When the indicating portion 129 is moved to the "Fast" setting, then the lever 100' is moved to the position shown by the dotted lines and in accordance with the previous description, it will now be obvious that the apparatus is set for the fast operation.

60 The movement of the outside indication portion 129 to the "Stop" position will cause the lever to move to a position intermediate between the "Slow" and "Fast" settings and again in accordance with the principles outlined in connection with Figures 1 to 6, the operative connection between the turntable and the motor drive will be broken and the turntable will no longer be rotated by the motor.

65 Still another modification of the same embodiment of the invention is possible within the spirit of the invention, which involves the rotation of the center of the idler 50 about the center of

the idler 51. Again the same type of mechanism is mounted upon the floating mounting plate including the mounting of one of the idlers 50 so that its center is rotatable about the center of the idler 51 and the mounting of the idler 51 so that it rotates about pin 81 and sleeve 80. Instead, however, of using a lever 100 or a lever 100' to effect the adjustment, the base of the sleeve 80 is widened and is extended into the form of the gear segment 150 as shown in Figures 8 and 10.

The rotation of the gear segment 150 to each of the three different positions hereinbefore described will produce the three different operations of "Fast," "Slow" and "Stop" hereinbefore described and for this purpose another gear segment 151 is utilized in order to rotate the gear segment 150.

The other gear segment 151 is fixedly attached to a pin 152 which is journaled in a sleeve 153. The opposite end of the pin 152 is fixedly secured to a handle and indicator 154. Rotation of the handle and indicator 154 will result in corresponding rotation of the gear segment 151, and the meshing of the gear segment 151 with the gear segment 150 will serve to transmit rotative power to the gear segment 150 and hence to rotate the sleeve 80 in the manner hereinbefore described and for the purposes hereinbefore described.

In the embodiment shown in Figures 8 and 10, the turntable 40 is again shown mounted in a depression 120 although, of course, the same type of operation may occur whether or not the turntable happens to be mounted in a depression. When the handle 154 is rotated to the "Slow" setting as shown in Figure 8, the gear segment 151 is rotated thereby and hence rotates the gear segment 150 in a clockwise direction, thus rotating the sleeve 80 in the manner hereinbefore described in connection with the other modifications and hence bringing the idler 50 into engagement with both the spindle of the motor and the flange of the turntable.

Here it will be noted that the gear segment 150 has been moved in the same manner as have the lever 100 of Figure 2 or the lever 100' of Figure 7; but that the handle 154 has been moved in the opposite direction to achieve this result owing to the reversal of the motion occasioned by the interposition of a gear.

When the handle and indicator 154 is rotated to the "Fast" position, the gear segment 151 is correspondingly rotated in a clockwise direction and the gear segment 150 is rotated in a counterclockwise direction in order to obtain the fast setting, the remaining members again being moved in the same manner as were the members of Figures 1 to 7.

Likewise when the handle 154 is moved to the "Stop" indication, the motion is transmitted to the gear segment 151 and therefrom to the gear segment 150 through which it is transmitted to the sleeve 80 and thence to the arm 90 and thence to the center of the idler 50 in order to produce again the position of the idlers shown in Figure 4.

In the foregoing description I have described not merely the essential invention which comprises utilization of two idlers, each engageable with a different diameter of the spindle and the rotation of one idler about the center of the other in order to move a selected idler into or out of engagement with both the spindle and the turntable, but I have also described various means for obtaining this result and various practical

commercial modifications of the primary idea. Many other uses and adaptations of the device herein described will now be obvious to those skilled in the art and hence I prefer to be bound 5 not by the specific disclosures herein but only by the appended claims.

I claim:

1. A speed changing drive for a turntable having a peripheral flange, said drive comprising a 10 source of motive power, a spindle driven thereby, a pair of friction wheels and a floating mounting therefor, said mounting being yieldingly biased toward the spindle, one of said friction wheels being rotatable about a fixed support on 15 said mounting, the other of said friction wheels being rotatable about a pin mounted eccentrically of the first of said friction wheels, said pin being movable about the said center of said first friction wheel to vary the distance of said pin 20 from the spindle.

2. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, said bearing being rotatable about a fixed support on said mounting, an arm secured to said bearing, the second of said friction wheels being rotatably mounted on said arm in a plane parallel to and above the first friction wheel, said second friction wheel being eccentric with respect to said first friction wheel and means for rotating said bearing to swing the center of said second friction wheel about the center of said first friction wheel.

3. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, said bearing being rotatable about a fixed support on said mounting, an arm secured to said bearing, the second of said friction wheels being rotatably mounted on said arm in a plane parallel to and above the first friction wheel, said second friction wheel being eccentric with respect to said first friction wheel and means for rotating said bearing to swing the center of said second friction wheel about the center of said first friction wheel, said second friction wheel constituting the driving connection between the spindle and flange when its center is nearer both the spindle and the flange than the center of the first friction wheel; and said first friction wheel constituting the driving connection between the spindle and flange when its center is nearer both the spindle and the flange than the center of the second friction wheel.

4. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, said bearing being rotatable about a fixed support on said mounting, an arm secured to said bearing, the second of said friction wheels being rotatably mounted on said arm in a plane parallel to and above the first friction wheel, said second friction wheel being eccentric with respect to said first friction wheel and means

for rotating said bearing to swing the center of said second friction wheel about the center of said first friction wheel, said second friction wheel constituting the driving connection between the spindle and flange when its center is nearer both the spindle and the flange than the center of the first friction wheel; said first friction wheel constituting the driving connection between the spindle and flange when its center is nearer both the spindle and the flange than the center of the second friction wheel, and there being no driving connection between the spindle and the flange when the center of the second friction wheel is nearer the spindle than the center of the first friction wheel and when the center of the first friction wheel is nearer the flange than the center of the second friction wheel.

5. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, 10 said bearing being rotatable about a fixed support on said mounting, an arm secured to said bearing, the second of said friction wheels being rotatably mounted on said arm in a plane parallel to and above the first friction wheel, 15 said second friction wheel being eccentric with respect to said first friction wheel and means for rotating said bearing to swing the center of said second friction wheel about the center of said first friction wheel, said means comprising an arm secured to said bearing and extending 20 beyond the periphery of the turntable.

6. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, 25 said bearing being rotatable about a fixed support on said mounting, an arm secured to said bearing, the second of said friction wheels being rotatably mounted on said arm in a plane parallel to and above the first friction wheel, 30 said second friction wheel being eccentric with respect to said first friction wheel and means for rotating said bearing to swing the center of said second friction wheel about the center of said first friction wheel, said means comprising an arm secured to said bearing and extending 35 beyond the periphery of the turntable.

7. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, said bearing being rotatable about a fixed support on said mounting, an arm secured to said bearing, the second of said friction wheels being rotatably mounted on said arm in a plane parallel to and above the first friction wheel, 40 said second friction wheel being eccentric with respect to said first friction wheel and means for rotating said bearing to swing the center of said

second friction wheel about the center of said first friction wheel, said means comprising a gear segment secured to said bearing, a second rotatable gear segment engageable with said first gear segment, and a handle and indicator secured to said second gear segment for rotating the same.

8. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, 45 said bearing being rotatable about a fixed support on said mounting, an arm secured to said bearing, the second of said friction wheels being rotatably mounted on said arm in a plane parallel to and above the first friction wheel, 50 said second friction wheel being eccentric with respect to said first friction wheel and means for rotating said bearing to swing the center of said second friction wheel about the center of said first friction wheel, said second friction wheel constituting the driving connection between the spindle and flange when its center is nearer both the spindle and the flange than the center of the first friction wheel; and said first friction wheel constituting the driving connection between the spindle and flange when its center is nearer both the spindle and the flange than the center of the second friction wheel, and there being no driving connection between the spindle and the flange, when the center of the second friction wheel is nearer the spindle than the center of the first friction wheel and when the center of the first friction wheel is nearer the flange than the center of the second friction wheel, said mounting being automatically adjustably positioned with respect to each position of the friction wheels.

9. A speed changing drive for a turntable having a peripheral flange, said drive comprising a source of motive power, a spindle driven thereby, a pair of friction wheels and a floating mounting therefor, said mounting being yieldingly biased toward the spindle, one of said friction wheels being rotatable about a bearing, 55 said bearing being rotatable about a fixed support on said mounting, an arm secured to said bearing, the second of said friction wheels being rotatably mounted on said arm in a plane parallel to and above the first friction wheel, 60 said second friction wheel being eccentric with respect to said first friction wheel and means for rotating said bearing to swing the center of said second friction wheel about the center of said first friction wheel, said second friction wheel constituting the driving connection between the spindle and flange when its center is nearer both the spindle and the flange than the center of the first friction wheel; and said first friction wheel constituting the driving connection between the spindle and the flange when its center is nearer both the spindle and the flange than the center of the second friction wheel, 65 said spindle being of restricted diameter at the upper portion thereof at the area of engagement with the second friction wheel and being of larger diameter at the lower portion at the area of engagement with the first friction wheel.

PAUL STEAD GAY.
